UNITED STATES PATENT OFFICE.

WILLARD MCKEE, OF CHARLESTON, WEST VIRGINIA.

COMPRESSED-AIR WATER-ELEVATOR.

SPECIFICATION forming part of Letters Patent No. 712,401, dated October 28, 1902.

Application filed April 10, 1902. Serial No. 102,211 (No model.)

To all whom it may concern:

Be it known that I, WILLARD MCKEE, a citizen of the United States, and a resident of Charleston, in the county of Kanawha and State of West Virginia, have made certain new and useful Improvements in Compressed-Air Water-Elevators, of which the following is a specification.

This invention is an improvement in compressed-air water-elevators, and relates particularly to the valve mechanism whereby the compressed air is admitted to the pumping-chambers and permitted to exhaust therefrom in the operation of the apparatus; and the invention consists in certain novel constructions and combinations of parts, as will be hereinafter described and claimed.

In the drawings, Figure 1 is a front elevation of the apparatus. Fig. 2 is a vertical transverse section thereof on about line 2 2 of Fig. 3. Fig. 3 is a top plan view of the pump. Fig. 4 is a detail perspective view of one of the operating-valves. Fig. 5 is a detail vertical section on about line 5 5 of Fig. 3, illustrating one of the operating-valves and the casing therefor. Fig. 6 is a detail section on about line 6 6 of Fig. 2. Fig. 7 is a detail section on about line 6 6 of Fig. 2 looking in the opposite direction from Fig. 6. Figs. 8 and 9 are detail perspective views showing the inner sides of the opposite side casings. Fig. 10 is a detail perspective view of the front end of the main valve-casing. Fig. 11 is a detail perspective view showing the rear end of the valve-casing. Figs. 13 and 15 are elevations of the inner faces of, respectively, the left and right side casings. Figs. 12 and 14 are detail cross-sections on, respectively, lines 12 12 and 14 14 of Fig. 13; and Figs. 16 and 17 are detail cross-sections on, respectively, lines 16 16 and 17 17 of Fig. 15.

In the construction shown I employ two cylinders 10 and 11, which provide what for convenience of reference I term the "pumping-chambers." These chambers are provided with valve-inlets 10^a and 11^a and have outlet-pipes 12 and 13, provided at 12^a and 13^a with suitable check-valves and communicating with a discharge-pipe 14, by which the water may be conducted to any suitable point. Floats 15 and 16 operate in the chambers 10 and 11 and slide vertically on rods 17 and 18,

which are provided with upper and lower abutments 17^a, 18^a, 17^b, and 18^b, which abutments are engaged by the floats when the latter are in their uppermost and lowermost positions in order to operate the rods up or down, as may be desired. The rods 17 and 18 may be balanced by the weighted levers 17^c and 18^c, as shown in Fig. 2. At their upper ends the pumping-chambers 10 and 11 communicate by the pipes 19 and 20 with the side casings, in which the operating-valves are supported and turned, as presently described. The pipes 19 and 20 preferably communicate with chambers 21 and 22 in the side casings I and I', and the rods 17 and 18 extend through the pipes 19 and 20 and connect, respectively, with crank-arms 23 and 24 on, respectively, the valves C and C'. In operation it is desired that one pumping-chamber should be discharging as the other fills, it being understood that these chambers are submerged in the water to be pumped and that the water will enter the said chambers by gravity and rising therein will lift the floats until they engage their upper abutments, at which time the floats will lift the rod and adjust the crank-arms of the operating-valves to the position shown at the right in Fig. 2. Then when the chamber has been emptied by the pressure of the compressed air its float will engage the lower abutment of its rod and will operate the said rod to adjust the crank of its operating-valve to the position shown at the left in Fig. 2. In Fig. 2 the chamber at the left is shown as filling, while the chamber at the right is shown discharging, the chamber at the left being about one-sixth filled, while about one-sixth of the contents of the chamber at the right has been discharged. By the valve mechanism presently described I control admission of compressed air to one chamber to discharge its contents, while the air in the other chamber is exhausting as such chamber fills with water.

As shown, the construction includes two similar main valves A A', a controlling-valve B, similar operating-valves C and C', and casings for said valves connected and operating as will be understood from the drawings and following description. The main valves and the controlling-valve operate within what for convenience of reference I term the "main-

valve casing," while the operating-valves operate in side casings I and I', secured alongside the main casing and communicating therewith in the manner described. The purpose of the main valves is to control the passage of compressed air to and from their respective pumping-chambers, and in doing this they are caused to establish communication in one position between the supply of compressed air and their respective pumping-chambers and in their other position to establish communication between their pumping-chambers and the exhaust, so compressed air will be admitted into the pumping-chamber to discharge the water therefrom, and then when said water has been discharged the main valve corresponding to such chamber will be readjusted to permit the air in said pumping-chamber to exhaust, so the said chamber can refill as desired. I arrange the main valves so one will be supplying compressed air to its pumping-chamber while the other valve is discharging the exhaust-air from its chamber, the operation being practically continuous, as will be understood from what follows. The purpose of the controlling-valve is to prevent the passage of compressed air to the main valve of one pumping-chamber until such main valve shall have been adjusted into position to feed air to its chamber and the opposite main valve has been adjusted to full-exhaust position, and I accomplish this by connecting the cylinders for the main valves with the cylinder for the controlling-valve, as will be presently described. The purpose of the operating-valves is to control the positions of the main valves by permitting the passage of compressed air to one or the other ends of the said main valves, according to the positions of the operating-valves. The operating-valves rock in their cylinders, while the controlling-valve and the main valves are movable longitudinally in their cylinders.

The casing E for the main valves and the controlling-valve is shown in detail in Fig. 10 and is provided with the cylindrical openings a, a', and b for the valves A, A' and B, has an inlet-port E' in its top centrally between its ends and communicating with the chamber b, and an exhaust-port E² in its lower side centrally between its ends, which communicates by branches e and e' with the valve-chambers a and a'. In its front end the body E of the main casing has grooves or channels F and F', which communicate by ports or passages f and f' with the feed-port E' and receive the supply of compressed air therefrom and extend at their outer ends at F² and F³ to the opposite edges of the casing E and communicate with ports or passages in the side casings for the controlling-valves. At its front end the chamber a communicates, through a port G, with the chamber b, while the rear end of the chamber a' communicates, through a port G', with the rear end of the chamber b, as shown in Fig. 11. Ports H and

H' are formed in the front end of the casing E and lead outwardly, respectively, from the chambers a and a' to the outer edges of the casing E, and similar ports h and h' lead outwardly from the opposite or rear ends of chambers a and a' to the sides of the casing E. The side casings I and I' for the valves C and C' fit at their inner sides against the opposite sides of the casing E, and front and rear end or cap plates M and N are applied to said casings E, I, and I', as shown in the drawings. The side casings I and I' are alike except that they are rights and lefts. I will describe the casing I, (shown in Figs. 8 and 13 and at the left in Fig. 2,) and the description thereof, in connection with the main casing E, will suffice to an understanding of this feature of my invention. In the face i of the casing I, I provide grooves J, K, and L, which form passages for the compressed air and are elongated in the direction of length of the casing I and all of which communicate with the chamber for the valve C. The grooves K and L extend to the front end of the casing I and communicate, respectively, with the passages H and F, so the compressed air supplied through the passage F will be conducted by the groove L and delivered, through a port L', to the chamber for the valve C. The valve C may be an ordinary rocking valve suitably ported for adjustment in one position to direct the compressed air supplied through port L' through the feed-port K' and passage K to the passage H to operate in front of the valve A or in the other position to deliver the compressed air supplied through the port L' through the feed-port J' to the passage J, whence it will be delivered through port h to operate in rear of the valve A, as will be understood from Figs. 8 and 10. It will be noticed from Fig. 9 that the casing I' is similar to the casing I and is supplied with passages j, k, and l, corresponding to the passages J, K, and L of the casing I. The passages J and K are provided with exhaust-ports J² and K², and the valve C is suitably constructed to properly exhaust in the operation of the apparatus.

In the operation of the described construction if the valves C and C' are adjusted to deliver the compressed air supplied through the passages F and F' through the passages J and j to operate in rear of the valves A and A' said valves will be moved forward to the front ends of their chambers a and a' and the feed-port 1 of the valve A' will be adjusted into register with the port 2 of the casing I' and also into register with the feed-port 3, registering with the port 4 of the controlling-valve, so the compressed air will pass from the port E' directly to the chamber at the right in Fig. 2. At the same time the port 5 of the valve A will be registered with the feed-port 6 of the casing I and also with the exhaust-port E², so the air in the pumping-chamber at the left in Fig. 2 can exhaust while the said chamber is filling, as will be understood from said figure. It will be no

ticed that each of the valves A and A' has a feed-port and an exhaust-port. The feed-port of the valve A' is in rear of its exhaust-port, while the feed-port of the valve A is in advance of its exhaust-port, so that if the valves be pushed back from the position shown in Fig. 2 to their rearmost position the valve A will be adjusted into feed position to deliver compressed air to its pumping-chamber, while the valve A' will be adjusted to exhaust, it being understood that in the operation of the device when one chamber empties just as the other is filled the valves A and A' move back at the same time and to the front at the same time; but if one chamber fills before the other empties the valves C or C' of the said filled chamber will be adjusted to move its corresponding main valve endwise; but the other main valve will remain in position to supply its chamber with compressed air until such chamber has emptied. This is effected by the controlling-valve B, which is movable back and forth in its chamber b, which chamber b communicates at one end through a port G with the valve-chamber a and at its other end through a port G' with the valve-chamber a'. If now the valve C, for instance, is adjusted in its casing I to supply air through the passages K and H to the front end of valve A, such compressed air will pass through the passage G to operate on the front side of the valve B. This pressure of air in front of the valve B would tend to force said valve to the rear except for the pressure supplied to the rear of the said valve B through the adjustment of the valve C' to supply air through the passages j and h' to the rear end of chamber a' and thence through the passage G' to the rear end of the valve B. Thus the pressures on the opposite ends of the valve B will neutralize each other and the said valve will remain in its fixed position until the valve C', in the present instance, will be adjusted to exhaust the air from the rear end of the valve B through the passages G', h', and j, so the pressure in front of the valve B will force said valve back. It will thus be understood that the purpose of the valve B is to control the supply of compressed air or the passage of such air to one or the other valve, so the main valve of one pumping-chamber will not receive compressed air until the other pumping-chamber has entirely emptied.

55 The valves C and C' are supplied with crank-handles O and P, so they can be conveniently operated to any desired position in starting the pump or at any other time desired, as in case the valves should by moving the pump or from other cause become displaced.

In operation it will be understood the chambers 10 and 11 are submerged and the operation proceeds as before described, one chamber emptying, as at the right in Fig 2, while the other fills, as shown at the left in said figure. If at any time the level of water

should fall, the water in the chamber which is emptying, as at the right in Fig. 2, will be discharged and then both chambers will fill 70 to the level of the water and the pump will stand at rest until the water rises high enough to again start the pump by the engagement of the floats with their upper abutments 17^a or 18^a. At such time both chambers 10 and 75 11 will be full, and the chamber 10 will proceed to empty, provided the chamber 11 was the last to discharge, as would be the case in the position of parts shown in Fig. 2, and the operation will then proceed with the chambers 10 and 11 discharging alternately, as desired.

While I have shown my pump as a double-chamber pump, it will be understood that the invention may be carried out in a single 85 chamber having its operating and main valve, and it will also be understood that if in the use of the double pump one side should for any cause become disabled the pump can proceed to operate as a single pump. 90

Having thus described my invention, what I claim as new, and desire to secure by Letters Patent, is—

1. A water-elevator comprising the pair of pumping-chambers having inlet and discharge 95 openings, the floats operating in said chambers, the operating-valves, means for operating said valves by their respective floats, the main valves and the controlling-valve, the casings provided with chambers for said 100 valves and with feed and exhaust ports and with ports or channels for the passage of compressed air through the controlling and main valves to the pumping-chamber and for the passage of pressure controlled by the position 105 of the operating-valves for moving the controlling-valve and main valves into different positions substantially as set forth.

2. The combination of the main-valve casing, having a chamber for the main valve, 110 and having ports or passages leading to its outer edges, and formed in its ends, the main valve in said chamber, the side casing provided in its inner face with ports or passages leading to its ends, and fitting at its inner 115 side against the side of the main-valve casing, the end plates or caps fitting against the ends of the main-valve casing, and the side casing and closing the ports or passages therein, and the operating-valve, substantially as set forth. 120

3. The combination with the main valve and its casing, having ports or passages H and h on its ends, the operating-valve and its casing, provided in its inner side with passages K and J registering respectively with the passages H and h in the main-valve casing, the 125 passages F and L being provided for the passage of pressure to the operating-valve, substantially as set forth.

4. The combination in a water-elevator of 130 the main valves, the controlling-valve controlling the passage of pressure to said main valves, the operating-valves and means whereby the said operating-valves may be oper-

ated, ports and passages being provided whereby the operating-valves control the passage of pressure to adjust the main valves and the controlling-valve to different positions substantially as set forth.

5. The combination of the main valves, the controlling-valve, the casing for said valves provided at its ends with passages or channels for the passage of pressure to the opposite sides thereof, the operating-valves, the side casings therefor having chambers for the operating-valves and fitting alongside the main-valve casing, ports or passages being provided between the side casings and the main-valve casing for the passage of pressure to and from the operating-valves substantially as set forth.

6. The combination with the main-valve casing having chambers for the main valves and for the controlling-valve and having ports connecting one end of one main-valve chamber with one end of the controlling-valve chamber and the opposite end of the other main-valve chamber with the other end of the controlling-valve chamber, the main valves and the controlling-valve operating in their chambers and means for controlling the passage of pressure to the main-valve chambers whereby to operate the main and controlling valves substantially as set forth.

7. The combination of the main-valve casing provided with chambers for the main valves and the controlling-valve and having ports F^2 and F^3 for the passage of pressure to the operating-valves and ports h and H and h' and H' for the passage of pressure to the opposite ends of the main-valve chambers and provided with the passages G and G' , the

main valves, the controlling-valve, the operating-valves, and the side casings having 40 chambers for the operating-valves and provided with ports or passages communicating with the passages F^2 , F^3 , H , H' , h and h' , substantially as set forth.

8. The combination with the main-valve 45 casing having chambers for the main valves and for the controlling-valve and having ports or passages leading to its outer edges and formed in its ends, the main and controlling valves, the side casings and their 50 valves, such casings being provided in their inner faces with ports or passages leading to their ends, and fitting at their inner sides against the opposite sides of the main-valve casing, and the end plates or caps fitting 55 against the ends of the main-valve casing and the side casings and closing the ports or passages substantially as set forth.

9. The improved pump herein described, comprising the pumping-chambers, their 60 floats, the main valves, the controlling-valve, the operating-valves, means whereby the floats operate their respective operating-valves, and the main-valve casing and side casing having valve-chambers and ports or 65 passages whereby the operating-valves can control the passage of pressure to effect the adjustment of the main valves and the controlling-valve to different positions substantially as set forth.
